PIPE WRENCH HAVING SLIDING LINK AND
PIVOTED JAW PIECE

Holly G. Greathouse, Dawes, W. Va.

Application October 10, 1947, Serial No. 779,105

1 Claim. (Cl. 81—126)

1

This invention relates to a tool especially adapted for use in oil field work and more particularly to a tubing tong or wrench which may be effectively and safely employed without danger of slippage on a pipe or tube and which in spite of applying great gripping pressure to the pipe or tube will not cut or deform it.

More particularly, it is an object of the present invention to provide a tool for use in making up joints in running pipe or tubing in wells which is especially durable and which may be operated even though certain of the parts thereof become broken.

Various other objects and advantages of the invention will hereinafter become more fully apparent from the following description of the drawings, illustrating a presently preferred embodiment of the tool, and wherein:

Figure 1 is a side elevational view thereof;

Figure 2 is a top plan view of the tool;

Figure 3 is a bottom plan view of the same;

Figure 4 is a side elevational view, partly in longitudinal section and showing the movable jaw of the tool in a partly retracted position, and

Figure 5 is an exploded perspective view showing the tool parts disassembled.

Referring more specifically to the drawings, the improved tongs or wrench is designated generally 6 and includes a head or body, designated generally 7, the forward end of which is restricted and curved downwardly and inwardly to form a hook-shaped fixed jaw 8 the concave work engaging face 9 of which is provided with spaced dies 10 which are embedded therein, transversely thereof and which protrude beyond the face 9 for biting engagement with a pipe or tube, not shown when the tool 6 is in an applied position.

The opposite, shank end 11 of the tool head or body 7 is enlarged and provided with a rearwardly opening recess 12 and a longitudinally extending bore 13 of non-circular cross section the rear end of which opens into said recess 12 and the forward end of which opens into the recessed portion 14 of the wrench head 7. The bottom portion 15 of the shank 11 forms a detachable section which is connected thereto by fastenings 16 for exposing the lower portion of the bore 13 and the bottom of the recess 12 when said shank section 15 is detached. As best seen in Figure 5, the rear end of the detachable section 15 is thickened on its underside as seen at 17 and grooved at 18 on the upper side of said thickened portion so that the groove 18 forms the lower part of the recess 12.

2

A handle 19 has an enlarged inner end which extends into the recess 12 and which inner end is provided with a notch 20 forming an upper apertured projection 21 through which extends a pivot pin 21' which is anchored in the shank portion 11 for pivotally mounting said handle in substantially end-to-end relationship to the head 7. Said inner end of the handle 19 is provided with a lower extension 22 from the upper inclined side of which projects an eye fastening 23 to which is anchored one end of a contractile coiled spring 24 which is anchored at its opposite end to an eye fastening 25 secured in the body 11 and which projects into the recess 12.

The sides of the lower handle extension 22 are recessed as seen at 26 to receive the corresponding ends of a pair of links 27 which are connected thereto by fastenings 28. A push rod 29 is reciprocally and non-rotatably disposed in the bore 13 and has a recessed rear end 30 receivable between the free ends of the links 27 and pivotally connected thereto by fastenings 31. The forward end of the push rod 29 is disposed between a pair of rearwardly projecting ears 32 of a jaw 33 and is connected thereto by a fastening 34. The push rod 29 is provided with an upwardly projecting lip 35 at its forward end to afford a substantial bearing surface for receiving the pressure of the movable jaw 33 when in an applied position. A forward or work engaging face 36 of the jaw 33 is concave and is preferably toothed or serrated.

From the foregoing it will be readily apparent that the spring 24 will normally urge the handle 19 in a clockwise direction, as seen in Figures 1 and 4 for retaining the movable jaw 33 in a projected position. Accordingly, the handle 19 must be swung counterclockwise with respect to the head 7 for applying the tool to a pipe or tube and when manual pressure is released therefrom, spring 24 by rocking the handle clockwise will project the push rod 29 and jaw 33 sufficiently to maintain the tool applied and as pressure is applied tortionally in a clockwise direction to the handle 19 for rotating the pipe or tubing engaged thereby, the push rod 29 and jaw 33 will be further urged toward a projected position for effectively clamping the tool to the work piece to prevent slippage thereof. As this tortional pressure is applied, for advancing the jaw 33, the upper edge thereof will ride along the inner surface of the head 14 of the recess which is disposed at a slight angle to the bore 13 so that the end 35 of the push rod will move into bearing engagement with the back side of the jaw 33 to relieve the pressure on the fastening 34 and the

handle portion 22 will move into engagement with the rear end of the push rod for relieving the pressure on the fastenings 28 and 31. By the simple expedient of turning the handle 19 counterclockwise relatively to the head 7, the jaw 33 can be retracted for disengaging the tool head 7 from the work piece.

It will be readily obvious that the tool will still function even if the spring 24 is broken although it will not maintain itself in an applied position and various other parts may be rendered damaged or inoperative without preventing use of the tool.

Various modifications and changes are contemplated and may obviously be resorted to, without departing from the spirit or scope of the invention as hereinafter defined by the appended claim.

I claim as my invention:

In a pipe tongs or wrench, an elongated head having a longitudinally extending recess adjacent to one of its ends opening outwardly of both sides and one edge of the head, said head having a hook shaped portion defining one end of said recess and forming a stationary jaw of the tool, the opposite end of said head having a recess opening outwardly thereof, said head having a longitudinal bore opening at one end into the opposite end of the first mentioned recess and having its opposite end opening into the last mentioned recess, an elongated handle member pivotally mounted at one end thereof in said last mentioned recess and projecting therefrom, a push rod recip-

rocally disposed in said bore, said handle member having a portion adjacent its pivoted end pivotally connected to one end of said push rod, the opposite end of said push rod being disposed in said first mentioned recess, a movable jaw connected to the last mentioned end of said push rod for limited pivotal movement relatively thereto and supported by the push rod for sliding movement in the first mentioned recess toward and away from said stationary jaw for cooperation with the stationary jaw for engaging a workpiece, and means whereby a portion of the push rod will move into abutting engagement with the movable jaw as the latter approaches the stationary jaw.

HOLLY G. GREATHOUSE.
